UNITED STATES PATENT OFFICE.

MILTON J. PORTER, OF WAYNE, PENNSYLVANIA, ASSIGNOR OF ONE-HALF TO JOSEPH M. FRONETFIELD, OF WAYNE, PENNSYLVANIA.

POST-OFFICE BOX.

1,314,363.

Specification of Letters Patent. Patented Aug. 26, 1919.

Application filed February 6, 1918. Serial No. 275,379.

To all whom it may concern:

Be it known that I, MILTON J. PORTER, a citizen of the United States, and a resident of Wayne, county of Delaware, State of 5 Pennsylvania, have invented certain Improvements in Post-Office Boxes, of which the following is a specification.

My invention relates to certain improvements in post office boxes, particularly those 10 which are arranged in nests, open at the rear and having doors at the front end which are opened by the renters of the boxes.

One object of my invention is to provide 15 means for preventing the accidental placing of mail matter in unrented boxes. This object I attain by providing a shutter, or closure, which can be adjusted so as to close the rear of any box in the nest, its primary 20 function being to close the rear of "unrented" boxes.

A further object of the invention is to provide a closure for each box and to construct the closure so that it will carry the 25 name plate of the party renting the box.

The invention also relates to details in construction in which the closure, when the box is "rented" can be located in the upper portion of the box so as not to interfere with 30 the placing of mail in the box.

In the accompanying drawings:

Figure 1 is a rear view of a case, showing a nest of post office boxes;

Fig. 2 is a sectional view on the line 2—2, 35 Fig. 1, drawn to an enlarged scale;

Fig. 3 is a perspective view of one of the ends of the boxes, showing the device in position to close the box;

Fig. 4 is a similar view, showing the device in the raised position;

Fig. 5 is a detached, inverted, perspective view of the slide in which the closing device is mounted;

Fig. 6 is a detached perspective view of 45 the closing device;

Fig. 7 is a sectional view of the same;

Fig. 8 is a view of the blank for the closing device prior to being bent into shape;

Fig. 9 is an enlarged sectional view of one 50 of the devices on the line 2—2, Fig 1; and

Figs. 10 and 11 are views of a modification.

Referring to the drawings, 1 is a nest of boxes, which may be constructed either of 55 wood or of metal. The boxes are usually

closed at their outer ends by suitable doors 2, the key of which is held by the renter of the box. The rear of each box is open and is usually in front of the sorting table at the post office so that the postmaster can 60 place the mail in the respective boxes. These boxes are rented to persons receiving the mail and there are usually more boxes than renters, consequently, some of the boxes remain unrented. These unrented boxes are 65 located at any point in the nest of boxes. Therefore, it frequently happens that the postmaster inadvertently places mail in one of the unrented boxes, as well as in the rented boxes. Such a mistake is quickly 70 corrected if the mail be wrongly placed in a "rented" box, as the renter, when he calls for his mail, will return the misplaced mail to the postmaster, but the mail incorrectly placed in an "unrented" box is likely to remain for some time without being discovered.

By my invention, I provide a simple closing device for all unrented boxes so that it is impossible to place mail in them. 80

I will now proceed to describe the details of construction.

Secured to the upper portion of each box is a bearing plate 3 having ways 4 at each side, which terminate at the rear end in depending sockets 5. Extending from the ways 4 are supporting members 6 for the closing device. This bearing plate is made of sheet metal, bent to form the elements hereinbefore described, and is secured to the upper surface of each box with the sockets 5 projecting downward at the rear end. The closing device, in the present instance, consists of a sheet metal plate 7 having a cross bar 8 at one end, which is adapted to the 85 ways 4 in the bearing plate and is designed to drop into the sockets 5 when the plate is fully extended. This prevents the accidental moving of the plate from its position. The end of the plate is bent up, as at 9, not only to form a stop and a means by which the plate can be readily handled, but also to form a carrier to receive a card indicating the number of the box and the renter's name. The plate is bent from a 90 blank shown in Fig. 8, one end, 10, of the blank being bent around a bar 8, while the other end of the blank is turned up to form the portion 9. In order to form the lips on the plate to hold the card, I make the blank 95

100

105

110

with an extension 11 and slot the blank at 12, and bend these portions so as to form the lips, as clearly shown in Figs. 6 and 7, in which a card, or name plate, can be inserted.

5 The object of providing the closing device with a name plate is that the moment the rental of the box ceases and it is closed by the closing device, the name of the previous renter disappears. When the box is 10 rented again, all that is necessary is to elevate the closing device to a horizontal position and to slide it in the ways 4 of the bearing plate, the new renter's name occupying the space previously occupied by the 15 name of the former renter. The rod will hold one end of the closing device, while the projections 6 on the bearing plate will hold the body portion of the plate in position, as it will be understood that, in the 20 present instance, the width of the closing device is less than the width of the ways, so as to allow it to slide and hang freely.

While I prefer to provide each box with a closing member, in some instances each 25 box may be provided with guideways and the closing device may be detachable, and fewer in number than the boxes, as, in most cases, a number of the boxes are always rented.

30 In Figs. 1 to 4 of the drawings, I have illustrated my invention as applied to a nest of boxes, in which the divisions are made of wood. If they are made of metal, then the guideways for the closing device 35 may be formed in the metal partitions, or by angle bars 4^a, Figs. 10 and 11, and if the horizontal partitions are narrow, then the name plate or carrier 9^a on the plate 7^a may be depressed, as shown in Fig. 10, so 40 that when it is in the raised position the name carrier will be below the top of the box.

I claim:

1. The combination of a nest of post office boxes, each box having a door at one end 45 to be opened by the renter and open at the opposite end for the insertion of mail by a postmaster; a closing device for each box, said closing device being pivoted to the upper end of each box so as to hang down at 50 the open end of the box to prevent the insertion of mail therein and arranged to be moved into position so as to be located in the upper portion of the box when the box is rented.

55 2. The combination in a series of post office boxes, of a bearing plate secured to the under side of each partition separating the boxes, said bearing plate having guideways at each side; a closing device having 60 a cross bar at one end mounted in the guides and arranged, when in one position,

to hang freely from the bearing plate at the open end of the box so as to prevent the insertion of mail in the box when unrented, the bearing plate having means for 65 supporting the closing device when in the raised position so as to hold the device in the upper portion of the box clear of the mail inserted in the box.

3. The combination in a post office box, 70 of a bearing plate mounted in the upper portion of the box and having guideways at one side, said guideways terminating in depending sockets; a closing device having a rod at one end adapted to the guideways, 75 said rod, when the closing device is moved out to its full extent, dropping into the sockets and preventing the accidental movement of the upper end of the closing device when in the closed position. 80

4. The combination in a post office box, 85 of a bearing plate adapted to be secured to the upper portion of the box, said plate being made of sheet metal bent to form a slide way at each side with depending sockets and having supporting members projecting from the slideways; and a closing device made of sheet metal and having a rod at one end adapted to the ways and turned up at the opposite end to form a name plate holder, 90 the closing device being supported, when raised, by the ways and the supporting members of the bearing plate, and, when in the closed position, the rod is located in the sockets and the lower part of the closing 95 device rests against the upper surface of the box.

5. The combination, with a post office box, 100 of slideways in the upper portion of the same, a closing plate for the open end of said box, lugs carried at one end of said plate and arranged to move in said slideways, and an upturned flange at the opposite end of said plate; said flange affording a grasping projection when the plate is in 105 the closing position and lying against the upper edge of the box when the plate is in the raised position.

6. The combination, with a post office box, 110 of slideways in the upper portion of the same, a closing plate for the open end of said box, lugs carried at one end of said plate and arranged to move in said slideways, an upturned flange at the opposite end of said plate; said flange affording a grasping projection when the plate is in the closing position and lying against the upper edge of the box when the plate is in the raised position, and retaining means carried by said flange. 115

In witness whereof I affix my signature.
MILTON J. PORTER.
